UNITED STATES PATENT OFFICE

JOHN A. MAXWELL, JR., OF LANCASTER, PENNSYLVANIA, ASSIGNOR TO FOLLMER, CLOGG & CO., OF NEW YORK, N. Y., A CORPORATION OF NEW YORK

CANE UMBRELLA

Application filed April 22, 1930. Serial No. 446,312.

The present device is a cane umbrella where the sheath may be made of silk fabric or cotton fabric or a fabric of mixed silk and cotton, or other textile material. This sheath 5 is so supported by the construction of the frame that its lack of stiffness is not objectionable. The sheath may be no different or more cumbersome than the standard sheath. A sheath intended to cause the umbrella to 10 simulate a cane, that contains stiff or bulky parts or is made of a stiff or bulky material is inadmissible in the manufacture of standard umbrellas. The sheath has to be removed to open the umbrella, and must then 15 be placed in the pocket, and so must be foldable into small bulk.

I have devised an umbrella where the frame has an enlargement of the stick below the 20 top notch to support the part of the ribs adjacent to the top notch, which extends substantially from the top notch to the top stop, and fills the space between the ribs and stick between these points. I enlarge the projecting ferrule end of the stick and, at the handle 25 next to the stick, I place an annular recess, just deep enough to allow the ends of the ribs to fit into it, so as to bring their outer sides flush with the remainder of the handle. Over the ribs and long enough to 30 cover them only, extends the silk or other fabric sheath. This sheath, when removed and compressed, will occupy a very small space.

Fig. 1 is an elevation of the umbrella with 35 the sheath on, the upper end of the sheath being slightly parted from the shoulder on the handle to show the position of the ribs. Fig. 2 is an elevation of the frame, the position of the stick and the filling piece which 40 lie back of the ribs being indicated by the dotted lines. Fig. 3 is an elevation of the stick with the additional elements that are requisite for my invention. Fig. 4 is a detail showing the portion of the umbrella at the 45 ferrule end without the sheath. Fig. 5 is a view of a portion of the handle and the ribs, also without the sheath.

The figures illustrate the umbrella in a cane 50 form and are positioned cane-wise. The description herein follows the ordinary way

in which an umbrella is described, the ferrule end being designated as the top.

At the ferrule end of the stick 1, is the thickened end 2, which is permanently attached to the stick, and so secure an enlarged projecting ferrule end of the stick. This thickened end extends upwards from the top notch 3. It may be built of any suitable material, such as polished wood. The upper end ⁵⁵ a has the appearance of a ferrule, which can be given in any suitable manner. The portion adjacent to the top notch 3, may be finished with a bead 5, that forms a stop against which fits the ring 6, that lies at the upper end of the sheath 7. This ring and bead should be inconspicuous. The filling piece 8, extends downwards to or near to the upper position of the runner stop 9, (or if there is no stop, where the upper notch of the runner would come on the stick) and is ⁶⁰ thick enough to support the ribs between the top notch and top stop 9. This filling piece 8, is tubular and fits around the stick. One of the troubles in making an umbrella to ⁶⁵ simulate a cane, is the fact that an umbrella cover, when the umbrella is closed and rolled has the folds of the umbrella cover lapping over very slightly, the ribs in the part of the umbrella lying adjacent to the top notch. As the lower portions of the folded umbrella ⁷⁰ are approached, the fold becomes much more extended, and toward the handle end a fold of the cover may extend more than completely around the umbrella. The lower part of the folded umbrella is also stiffened ⁷⁵ by the stretchers. The lower part of the umbrella is therefore sufficiently solid to hold the sheath firmly extended, without any filling piece. The upper part of the umbrella, however, has very little folded cover wrapped over the ribs, and the ribs are but weakly supported between the top notch and the joint where a stretcher and a rib are connected to each other. The filling piece 8, ⁸⁰ performs the function of giving the ribs and consequently the sheath a firm support where this support is needed.

The handle 11 has the annular recess 10, which lies at the stick end of the handle 11. It should be depressed below the general ⁸⁵ ⁹⁰ ⁹⁵ ¹⁰⁰ general

level of the handle sufficiently to cause the outer portion of the ribs 12, to lie flush with the upper portion of the handle 11; the handle should be so positioned on the stick 1, that the ends of the tips *b*—*b* of the ribs will lie close up against the shoulder *c*. The placket *p* in the sheath 7, is closed tightly by a suitable fastening such as the snapper 4.

The sheath is fastened at the handle end 10 and is drawn over the tips *b*, *b*, of the ribs and as closely as possible to the shoulder *c*, of the handle 11. It should be stretched tightly between the handle and the bead 5. The top notch 3, may advantageously be made 15 larger than in the standard umbrella, to give a more uniform diameter to the cane. The end piece 2 should be of substantially equal diameter with the top notch and it is advantageous to have these parts nearly equal in 20 diameter with the handle. In fact, the relative sizes of the parts of the frame may be revised from those in the standard form of umbrella, in order that the best results may be secured, in simulating a cane.

25 My invention is not limited to the details set forth above, but is as extensive as the claims.

I claim:

1. An umbrella having a frame comprising 30 a handle, a stick with an enlargement of the portion thereof extending beyond the top notch, ribs, runner and stretchers, said umbrella having in combination with said frame, a filler extending along the stick 35 from the top notch towards the position the runner will occupy when the umbrella is open, and of sufficient diameter to fill out the space beneath the ribs at this portion of the stick when the umbrella is closed, and to 40 support said ribs at said portion of the stick, said umbrella being adapted when furled to be contained in a sheath for the furtherance of the simulation of a cane.

2. An umbrella having a frame comprising 45 a handle, ribs, stretchers, a runner and a stick having an enlargement of its portion extending beyond the top notch, and having, in combination with said frame a filler consisting of a filling piece mounted upon said 50 stick, said filler extending from the top notch towards the position the runner will occupy when the umbrella is open and of sufficient diameter to fill out the space between the stick and the ribs when the umbrella is 55 closed, said umbrella being adapted to be covered, when furled, with a sheath for the furtherance of the simulation of a cane.

3. An umbrella having a frame comprising 60 a handle of substantially the diameter of the umbrella when the latter is furled, said handle having an annular notch at its upper end, of lesser diameter, a runner, ribs, stretchers and a stick having an enlarged portion extending beyond the top notch, said 65 umbrella having in combination with said

frame a filler extending along said stick from the top notch towards the position the runner will occupy when the umbrella is open, of sufficient diameter to fill out the space beneath the ribs at this portion of the stick, and to support said ribs at said portion of the stick when the umbrella is closed, said umbrella when furled being adapted to be contained in a sheath extending from said handle to the said top notch, for the furtherance of the simulation of a cane.
